UNITED STATES PATENT OFFICE

105,267

DESIGN FOR AN OVERNIGHT CASE

Milton W. Daub, New York, N. Y.

Application October 23, 1935, Serial No. 59,188

Term of patent 14 years

To all whom it may concern:

Be it known that I, Milton W. Daub, a citizen of the United States, residing in the Borough and county of Queens, city and State of New York, have invented a new, original, and ornamental Design for Overnight Cases, of which the following is a specification, reference being had to the accompanying drawing, forming a part thereof, in which:

Fig. 1 is a perspective view of an overnight case showing my new design in opened position;

Fig. 2 is a top plan view thereof in closed position; and

Fig. 3 is a fragmentary end view thereof in closed position.

The characteristic feature of the invention resides in the design of the hinged cover and in the

adjacent portions of the side walls of the case wherein said front hinged cover has curved extension portions at each end thereof, the marginal edges of the inner surface of said extension portions having flanges which engage the inner surface of the marginal edges of said side walls. The terminals of the side walls have cut-away portions to receive the inwardly turned extensions of the hinged cover when the latter is closed. Thus the cover, when closed, presents the appearance of a smooth, unbroken structure with curved edges which merge into the side walls of the case.

I claim:

The ornamental design for an overnight case as shown and described.

MILTON W. DAUB.
